UNITED STATES PATENT OFFICE

FOSTER MALIC POOLE, OF TULSA, OKLAHOMA, ASSIGNOR TO THE BROWN INSTRUMENT COMPANY, OF PHILADELPHIA, PENNSYLVANIA, A CORPORATION OF PENNSYLVANIA

PYROMETER WELL

Application filed April 27, 1927. Serial No. 187,004.

The general object of the present invention is to provide a pyrometer housing or well of improved construction. More specifically, the object of my invention is to provide a pyrometer housing or well especially adapted for use in high pressure oil and steam lines and characterized by the formation of different parts of such different materials that each part may have properties suitable for its use under the operating conditions to which it is subjected.

The various features of novelty which characterize my invention are pointed out with particularity in the claims annexed to and forming a part of this specification. For a better understanding of the invention, however, and the advantages possessed by it reference should be had to the accompanying drawings and descriptive matter in which I have illustrated and described a preferred embodiment of the invention.

The figure in the drawing is a view with parts broken away and in section of one embodiment of my invention. In the embodiment of my invention illustrated in the drawing the pyrometer housing or well proper consists of a hollow head portion C and an elongated tubular body portion B. The head C is screwed into a threaded opening A' in the wall of a tube or chamber A into which the body B extends. As shown the outer end of the head C is enlarged and made hexagonal in form to facilitate its adjustment by a wrench or other suitable tool. The head C is formed with a central opening C' having a threaded section at its outer end. Secured in the inner end of the opening C' is the tube B which is closed at its inner end. Projecting from the outer end of the head is a tube D having one end secured in the threaded section of the opening C' and its opposite end secured in a central opening in the lower portion of a terminal head E. Arranged within and coaxial with the tubes C and D is an elongated refractory tube E' open at both ends and having its outer end secured in the terminal head E. The refractory tube E' is slightly spaced from the tube B and is arranged with its outer end spaced from the closed end 50 of the tube B. A thermocouple E² extends

through the refractory tube E' and has its hot junction projecting from the inner end of the tube E' to a point adjacent the closed end of the tube B. The thermocouple terminals are connected to the terminal posts E³ and E⁴ secured to the terminal head E.

In accordance with the present invention, I form the head C of a material having a thermal coefficient of expansion at least as high and preferably higher than that of the material of the wall A to insure a tight joint between the head C and the wall of the opening A' under all conditions of operation, and I form the protecting tube B of a material more highly resistant to corrosion and high temperatures than any available material having a thermal coefficient of expansion as high as the material from which the head C may be made. In oil still apparatus for which my invention is especially suitable the high pressures and temperatures existing in operation ordinarily require that the tubes and chamber walls of the apparatus be constructed of steel. For such use, I ordinarily form the head C of aluminum bronze, which has a higher coefficient of expansion than steel and form the protecting tube B of a chromium-iron alloy known as stainless iron or ascoloy, which has a lower coefficient of expansion than steel or aluminum bronze, but is highly resistant to the corrosive action of hot oil or steam and high temperatures, is of high thermal conductivity and is strong so that the tube B may have thin walls even when exposed to high external pressure.

In prior constructions, pyrometer housing or wells have been made of various materials. In particular, they have been made entirely of ascoloy from a single piece of bar stock. But with the temperatures prevailing in oil still operating, ascoloy wells have been found unsatisfactory because of the difficulty or impossibility of making a suitable detachable connection between the head portion of the well and the tube or chamber wall through which the housing extends. The usual method of securing this type of well in position is by screwing the well into a threaded wall opening when the still is cold. As the well loosens up when the still is heated to the

100

normal operating temperature, approximately 850° F., say, because of the small coefficient of expansion of the ascoloy as compared with steel, it is necessary to tighten up the well as the higher temperatures are reached. When the still cools down and it is desired to remove the well for cleaning, the wall through which the well extends contracts more than the ascoloy well and the well becomes frozen in and can be removed only with great difficulty. In ordinary use, particularly in oil heating apparatus, frequent removals of the pyrometer well are required for tube and well wall cleaning and for other purposes.

With a material having a higher coefficient of expansion than steel, the well may be inserted in position when cold and when the wall A is heated up, the connection becomes tighter owing to the greater expansion of the head C than the wall A. On cooling down, the well can easily be removed, as the well head C contracts more than the wall A. It is essential to successful operation of a tube still that the connection between the pyrometer well and the pipe be very tight to prevent leakage of oil with resulting waste and danger of fire. In practical operation no material has been found having a higher coefficient of expansion than steel and also having sufficient resistance to corrosion and the strength and refractory properties required for commercial construction and use as a protecting tube.

Since the protecting tube B and the head C are formed of metals having different rates of expansion, it is necessary that those parts be so connected that there will be no practical possibility of the parts loosening under the conditions of use to which the apparatus is subjected. In the construction illustrated the protecting tube is shown as inserted in and welded to the head portion C.

The parts may be connected however, by shrinking the head on the open end of the protecting tube. In such case, the head C is first heated, and after the tube B is inserted in the opening C', the head is allowed to cool thereby forming a very tight connection between the parts. If the normal operation of the still apparatus requires a temperature not higher than 900° F., and if with this construction the parts are so proportioned that the head C must be heated to 1000° F. to get it on the tube B, then the joint between the parts will be secure under all normal operating temperatures. With the head C thus shrunk on the tube B additional security may be had by welding the parts together at the outer end of the joint between them.

My invention is characterized by the simplicity of the construction and the effectiveness of the apparatus when used. With the materials used, the parts perform their normal functions more efficiently for a longer

commercial period than is the case with the apparatus heretofore employed.

While in accordance with the provisions of the statutes, I have illustrated and described the best form of embodiment of my invention now known to me, it will be apparent to those skilled in the art that changes may be made in the form of the apparatus disclosed without departing from the spirit of my invention as set forth in the appended claims and that in some cases certain features of my invention may be used to advantage without a corresponding use of other features.

Having now described my invention, what I claim as new and desire to secure by Letters Patent, is:—

1. A pyrometer well comprising a head adapted to be secured in an opening in the wall of a container and made of a material having a relatively high thermal coefficient of expansion and an elongated tube portion secured to said head and formed of a material having a lower coefficient of expansion than the material of the container, but which is more highly resistant to corrosion than the head material.

2. A pyrometer well adapted for use in a container for a fluid under high temperature and pressure comprising a head portion adapted to be seated in an opening in the wall of the container and made of metal having a higher thermal coefficient of expansion than the metal of the container wall and an elongated tube portion secured to said head and formed of a metal having a lower thermal coefficient of expansion than the metal of the container wall and more highly resistant to the corrosive action of the fluid and high temperatures than the metal of said head portion.

3. A pyrometer well adapted for use in a container for a fluid under high temperature and pressure comprising a threaded head portion adapted to be secured in an opening in the wall of the container and made of metal having a higher thermal coefficient of expansion than the metal of the container wall and an elongated tube portion secured to said head and formed of a metal having a lower thermal coefficient of expansion than the metal of the container wall and more highly resistant to corrosion and high temperatures than the metal of said head and container wall.

4. A pyrometer well adapted for use in a container for a fluid under high temperature and pressure comprising an aluminum bronze head portion adapted to be secured in position in the wall of said container and an elongated tube portion secured to said head formed of a metal having a lower thermal coefficient of expansion than the material of the container wall and more highly resistant to corrosion and high temperatures than aluminum bronze.

5. A pyrometer well adapted for use in a container for a fluid under high temperature and pressure comprising an aluminum bronze head portion adapted to be secured in position in the wall of said container, 5 and an elongated ascoloy tube portion secured in said head and adapted to contact with said fluid.

6. A pyrometer well adapted for use in 10 a container for a fluid under high temperature comprising a head portion adapted to be seated in an opening in the wall of the container and made of a material having a thermal coefficient of expansion not less than 15 that of the material of the container wall and an elongated tube portion secured to said head and formed of a material having a lower thermal coefficient of expansion than the material of said container wall and highly 20 resistant to corrosion.

Signed at St. Louis, in the county of St. Louis and State of Missouri, this 23rd day of April, A. D. 1927.

FOSTER MALIC POOLE.
